UNITED STATES PATENT OFFICE

2,625,292

PERFUME BOTTLE CONTAINER

Donald L. Spender, Wolcott, Conn., assignor to
Scovill Manufacturing Company, Waterbury,
Conn., a corporation of Connecticut

Application October 22, 1949, Serial No. 122,972

6 Claims. (Cl. 220—31)

1

This invention relates to containers and more particularly to a container for holding a perfume bottle so that the latter can be conveniently carried about in a lady's hand bag or purse.

Perfume is usually conveyed in small ornamental and frangible bottles, and if carried about in a hand bag that is subjected to considerable rough usage and handling, there always exists the possibility that the bottle may be broken or the stopper of the bottle loosened or removed with the resulting loss of the contents and ruining or soiling the hand bag and its contents.

The object of this invention is to provide a suitable container for a perfume bottle that will permit the bottle to be carried about in a hand bag without being subjected to the above listed accidents or disadvantages.

A further object is to provide a container that will accommodate a bottle of particular design and present an article than can be conveniently handled and readily operated to expose the discharge end of the bottle for access to the bottle contents, and one that is strong and of attractive appearance.

Another object is to provide a special shaped container which is round shaped in one plane and oval shaped in the transverse plane and comprising two complementary similar shells hinged together on one broad side of the container and having detent lock connection on the opposite broad side of the container.

Other objects and advantages of the invention will be apparent as it is better understood from the following description which taken in connection with the accompanying drawing discloses a preferred embodiment thereof, and wherein,

Fig. 1 shows a perspective view of the container with the cover in open position to expose the bottle ready for use.

Fig. 2 is a front plan view of the container in closed position.

Fig. 3 is a back plan view.

Fig. 4 is a front view similar to Fig. 2 showing the cover in partly open position.

Fig. 5 is a transverse sectional view on a slightly enlarged scale taken along the line 5—5 of Fig. 2, and,

Fig. 6 is a fragmentary sectional view taken along the line of 6—6 of Fig. 2 to show the detent connection.

Referring now to the drawing in which like reference numerals denote like parts throughout the several views, the numeral 10 designates a

2

body shell and the numeral 11 a cover shell. These shells are drawn into cupped shape such that when the shells are assembled together they will present a container that will appear round shape in a plan view, and that will be substantially oval or elliptical shape in a transverse plane to the plan view, which latter shape is best shown in Fig. 5.

The body shell 10 consists of a front wall 12 and a back wall 13 and the shell terminating in an open end edge 14 which is located at about the mid horizontal plane of the container. The cover shell 11 likewise has a front wall 15 and a back wall 16 terminating in the bottom edge 17 that abuts against the open end edge 14 of the body shell when in closed position.

The back wall 13 of the body shell 10 has an integral portion that extends slightly upwardly above the open end edge 14 with inclined edges 18 and terminating in a flat edge 18a. Between the edges 18 and 18a there is provided a pair of spaced hinge barrel sections 19 (see Fig. 3). The back wall of the cover is cut out as at 20 complementary to the inclined edges 18 and straight edge 18a, and is provided with an integral hinge barrel section 21 that fits in between the barrel sections 19 and is connected thereto in the usual manner as by a hinge pin 22. By placing the axis of the hinge barrels 19 and 21 on a line above the mid horizontal plane of the container, ample room is allowed for the cover to hinge relative to the body without danger of interference with the bottle stopper 32, which axis, as best shown in Fig. 5, is disposed a considerable distance above the mid plane of the container.

The front wall 12 of the body shell is formed with an integral disc section 23 that is formed outwardly from the normal front plane of the body front wall 12 and is positioned so the upper half of the disc extends above the open edge 14 as shown in Figs. 2 and 4. This disc section can serve as a medallion plate to which any ornamental design may be affixed or embossed. The lower edge of the cover shell has a semi-circular cut-out 24 to accommodate the disc section 23. The upper end of the disc section is formed with an inwardly offset flange 25 that is adapted to underlie the front wall 15 of the cover adjacent the cut-out 24. The flange 25 at the point where it approaches the open end edge 14 is enlarged as at 26 on opposite sides of the disc section 23. These enlarged flange sections 26 are each provided with catch recesses 27 that are adapted to be engaged by a pair of complementary projecting nubs 28 that are formed inwardly of the front wall 15 of the cover, and the recesses 27 and

nubs 28 together provide a detent catch for the container.

In order to automatically open the cover 11 when the detent catches 27 and 28 are released, provision is made of a spring lug 29 that extends upwardly from the rear flat edge 18a of the body between the hinged barrel sections 19. This lug 29 is of arc shape to circumvent the cover hinge barrel section 21 and terminates in a lip 30 that is adapted to resiliently engage against the inner surface of the cover back wall 16, as shown in Fig. 5.

A comparable shaped perfume bottle 31, as shown in full in Fig. 1 and in dotted outline in Fig. 5, may be assembled into the body shell 10. The bottle will be provided with the usual form stopper 32. To assure that the stopper will not be loosened from the bottle under any circumstance, a resilient pad 33 of sponge rubber or cork, is assembled into the upper end of the cover shell 11 and may be adhesively held there in place. It will be apparent from Fig. 5 that the resilient pad 33 will be dimensioned to engage the adjacent end of the stopper 32, and by reason of the fact that the cover is held in locked position by the interengaging recesses 27 and projecting nubs 28, the resilient pad 33 will be firmly impressed against the stopper 32.

In order to operate the container and have ready access to the perfume bottle it is only necessary for the operator to press inwardly on the disc section 23 of the body shell 10 which will release the interengaging recesses 27 and nubs 28, whereupon the cover will automatically fly open by reason of the tension exerted by the spring lug 29. It will be appreciated that there will be considerable resiliency in the disc section 23 by reason of the fact that at least half the disc area extends above the open end edge 14 of the body shell 10.

While the container has been shown as round in one plane and oval in a transverse plane, it is to be appreciated that various other shapes of containers can be provided, the essential requirement being that the container is made of drawn shells having their closed base ends in opposed relationship to their open ends which are abutted together with the rear walls hinged together while the front walls are releasably interengaged by suitable detent catches.

It is, of course, obvious that minor changes in details of construction and arrangement of parts may be made without departing from the scope of the present invention as set forth in the appended claims.

I claim:

1. A container comprising body and cover shells substantially semi-circular in shape, both shells having front and rear walls joined together by a rounding connecting wall, said shells having open end edges abutted together when in closed position at the mid plane of said container, the rear wall of the body having an extension rising above the mid plane of said container, said cover rear wall having a complemental recess for receiving said extension, means hingedly connecting said extension to said cover rear wall, the front wall of said body having an escutcheon plate section formed outwardly of the wall thereof with a portion of said section extending above said mid plane, said cover front wall having a complemental cut-out to receive said escutcheon plate section, and means releasably interlocking said extended plate section to said cover front wall.

2. A container as defined by claim 1 wherein said escutcheon plate section is of circular shape with substantially half its area extending above the mid plane of said container.

3. A container as defined by claim 1 wherein said escutcheon plate section is of circular shape with substantially half its area extending above the mid plane of said container, and the extended portion of said plate section having an offset flange adapted to engage underneath the cover front wall recess when the container is in closed position.

4. A container as defined by claim 3 wherein said offset flange is of relatively narrow width around the upper part of said plate section and is increased in width on opposite sides of said plate section where the latter joins the front wall, and a part of said interlocking means being incorporated in the flange sections of increased width.

5. A container comprising hollow body and cover shells constructed to have their open ends in abutted relationship when in closed position at the mid plane of said container, both body and cover shells having broad front and rear walls and relatively narrow connecting end walls, the edges of the front and rear walls of the body shell having integral extensions rising above the open end of said body shell and the adjacent edges of said cover front and rear walls having complemental recesses for receiving said body shell extensions, the rear wall extension of said body shell being hingedly connected to said cover rear wall, said front wall extension and the adjacent portion of said body front wall being formed forwardly of said front wall to simulate an escutcheon, the front wall extension having an integral inwardly offset peripheral flange adapted to underlie the cover front wall adjacent its recess when in closed position, and means for releasably interlocking said body front extension flange to said cover front wall, said escutcheon serving as a thumb piece for releasing said interlocking means.

6. A container as defined by claim 5 wherein a lug member projects from the edge of the back wall of one of said shells, circumvents the hinge structure and is tensioned against the inside of the back wall of the other shell when the latter is in closed position for the purpose of automatically opening said cover upon release of the interlocking connection.
